MASCHINENGESELLSCHAFT MIT BEΣCHRÄNKTER HAFTUNG, OF BERLIN, GER-
MANY.

LINE-CASTING MACHINE.

1,027,826.

Specification of Letters Patent.

Patented May 28, 1912.

Application filed July 28, 1910. Serial No. 574,256.

To all whom it may concern:

Be it known that I, HEINRICH DREWELL, engineer, a subject of the German Emperor, residing at Charlottenburg, Germany, have 5 invented new and useful Improvements in Line-Casting Machines, of which the following is a specification.

This invention relates to line-casting machines, in which the molds for making the 10 line-bodies are accommodated in a wheel or similar rotatable holder and a primary object is to provide mechanism, by which several molds accommodated in one wheel can be changed automatically, the composer being 15 in a position to bring about the change at any time by one simple movement of a lever while composing.

The invention is particularly applicable to line-casting machines of the linotype system, as for example described in the United 20 States patent specifications 436,531, 436,532 and 557,000. In these machines the mold-wheel is generally rotated a quarter-revolution between the ejection of one line and the 25 casting of the next, the utilized mold being brought into the casting position from the ejection position. After a line has been cast, the mold-wheel is rotated three-quarters of a revolution more, whereby the mold and 30 the cast line are brought into the ejection position, in order to deliver the line into the line assembling galley.

Now according to this invention, instead of the mold-wheel rotating the standard 35 quarter-revolution it is rotated a different amount; when another mold is to be used instead of that used previously. This modified rotation of the mold-wheel may be a quarter-revolution in the opposite direction. 40 It will be readily understood that, in this event, instead of the utilized mold located in the ejection position another one, which is diametrically opposite to the previously-used mold, arrives into the casting position. 45 The invention may, however, be modified by a half-revolution or any other fraction of a whole revolution of the mold-wheel taking place instead of the quarter-revolution, or by the mold-wheel not rotating at all, and 50 a change of mold being hereby brought about.

In the illustrative embodiment of the invention described hereinafter it is assumed that the mold-wheel contains two molds at 55 diametrically opposite parts thereof. In

this case it is necessary for changing the mold that the wheel rotate a quarter-revolution backward before a line is cast, in order to bring the other mold into the casting position, instead of that mold opposite 60 to it, which has been previously utilized and which would be brought into the casting position by a quarter-revolution forward. For moving the mold-wheel backward its driving mechanism must be reversed by the 65 main shaft with the aid of reversing gear. The reversal must be done away with after the first quarter-revolution of the wheel, while this is stationary for the purpose of casting, in order that the following three-quarter revolution may take place in the customary direction, *i. e.* forward, and that the mold just utilized carrying the cast line may arrive into the ejection position and into the casting position again before the 70 next casting operation. A fresh reversal of the reversing gear causes a second change of mold to take place. Thus repeated reversal brings about as frequent a change of 75 mold.

The devices serving for reversing the direction of rotation of the mold-wheel must be constructed having regard to various points. For example, the composer can utilize capital letters of large font when 80 he has to set a line serving as title. In this event he will change the font at the beginning of the line. In another case, when one single word to be emphasized occurs in a line, the composer will only learn of the 85 necessity of changing the mold when he begins to set up this word and will then make the change. When he returns to the ordinary type after ending such a word, the change which has been prepared may not be 90 negatived. Further, the peculiarities of the casting apparatus in the machine have to be taken into consideration. When the composer begins a line, the previous line will be, as a rule, in the casting apparatus and 95 the latter is in operation, and during this time the driving gear of the mold-wheel may not be reversed. Again, the composer may have finished setting a line of matrices before the casting apparatus has delivered 100 the cast of the previous line; if the composer now begins a new line with a change of mold, this change may only be made when the previous line has been completely cast. 105 In this invention these requirements have 110

been taken into consideration, the change of mold being made dependent on the movement of the line-transferring carriage in such manner that the change only takes place when the line-transferring carriage moves out of its normal position for conveying a line into the first or casting elevator, but this can be so prepared by moving a lever or depressing a key, before or after the setting of a line or during the setting, that it must take place as soon as the line in question has been received by the line-transferring carriage and is conveyed to the place of casting. If the line-transferring carriage 15 be located, at the moment when the composer prepares the change of mold, in the intermediate position, *i. e.* in the so-called waiting position, in which the carriage is stopped by the casting apparatus which has 20 not yet returned into its normal position, the change of mold first occurs when the line of matrices in the waiting position is cast, and the cast is completely finished, and the line-transferring carriage carrying the following line arrives into the casting apparatus.

In matrix-setting and line-casting machines, the cast line is guided, as is known, after its ejection from the mold by a trimming device, the bur produced during casting being removed by the blades or cutters of the trimming device. The distance between these blades must correspond to the thickness of the line and therefore be 35 changed when the latter is changed. The thickness of the line depends on the width of the mold in which the line is cast. Therefore, as a rule, a change of mold necessitates a change in the adjustment of the 40 blades.

To this end, this invention comprises an automatic device for adjusting the cutters or blades for trimming lines in line-casting machines, in which the adjustment takes 45 place each time the mold is placed opposite the blades for the purpose of ejecting the line. The adjustment itself depends on abutments or stops which are arranged at the mold and have to be set specially at each 50 mold and cause the blades to be adjusted automatically corresponding to the width of the mold.

In order that the invention may be clearly understood, reference will be made to the accompanying drawings, wherein:

Figure 1 is a front elevation of a line-casting machine of the linotype system; Fig. 2 a side elevation of the same machine, and Fig. 3 an elevation of the reversing gear 60 of the mold-wheel, enlarged, as seen from the rear of the machine; Fig. 4 shows the reversing gear for rotating the mold-wheel backward, Fig. 5 is a side elevation of the reversing gear of the mold-wheel, and Fig. 6 shows the clutch device as seen from above

and partly in section through the parts of the clutch proper; Fig. 7 shows one single mold-wheel having two molds; Fig. 8 shows the so-called vise of the linotype line-casting machine seen from the inside, and in this vise, particularly, the line-trimming blades with the adjusting device, while Fig. 9 is a cross-section through the blade adjusting device taken on the line X—X in Fig. 8, and Fig. 10 is a like view except that the blades are here shown in the operative position.

Referring to the drawings, the line-casting machine of the linotype system which is illustrated in Figs. 1 and 2 and which is well-known in all the essential parts comprises a key-board A having the individual keys for releasing the matrices from the magazine B. The devices connecting the matrices with the keys are not relevant to the present invention and are therefore neither described nor illustrated. The matrices which are in the various channels of the magazine B fall, after being released, through guide channel C, partially directly and partially guided by a transferring belt D into the assembling elevator E and are placed in a row as one line. After the completion of a line this elevator E is raised and the line of matrices is caught by the fingers F of the line-transferring carriage and brought by way of the guide block G into the first or casting elevator H. This first conveys the line downward to in front of the place of casting where the line is justified in well-known manner and cast. The special devices which bring about the justification and casting are not relevant to this invention and are therefore not described. After a line has been cast the elevator H 105 brings it to the distributing place I whence it is conveyed into the second elevator K. This brings the line to the distributing device L above the magazine B, whence the individual matrices are conducted into the 110 corresponding channels of the magazine B.

The operation of the machine, as described, is well-known in all its details and described in the above mentioned patent specifications.

Referring firstly particularly to Figs. 1, 2, 3, 5 and 7, 1 designates the mold-wheel having the two molds 2 and 3 which can be brought alternately into the casting-position 5 indicated by dotted lines. The wheel rotates 120 around the axle 7, and is driven by a toothed wheel 4 secured on the shaft 8. In the old arrangement the driving shaft 8 of the wheel is rotated by a pinion 9 meshing with a toothed wheel 10. The latter is secured 125 on a shaft 11 which carries, in addition, a bevel wheel 12 driven in known manner by toothed segments 13 and 14 on the wheel 15. At the beginning of the entire casting operation, the segment 13 rotates the mold- 130

wheel a quarter-revolution. Afterward, by rotating the mold-wheel three-quarters of a revolution the segment 14 brings the cast line from the place of casting to the place of ejection. The wheel 15 is on the main shaft 16 of the machine, which shaft carries all the cams serving for controlling the casting apparatus. With the bevel wheel 12 is connected a rectangular member 17 (Figs. 3 and 6) which lies against the side face of the wheel 15 and brings about and maintains the exact adjustment of the gear wheels 12, 10, 4 and 9 and the mold-wheel 1. In the normal position of the main shaft the first tooth of the segment 13 meshes with the wheel 12 and as soon as the casting apparatus begins to operate drives the wheels 12 and 10 half a revolution. This movement causes the pinion 9, shaft 8 and wheel 4 to rotate one complete revolution and the mold-wheel 1 a quarter-revolution, the latter in the direction of the arrow 6 in Fig. 7.

In the new mechanism two gear wheels 10 and 18 are on the shaft 11 carrying the bevel wheel 12 and two corresponding pinions 9 and 19 are provided on the shaft 8. As in the known arrangement the gears 10 and 9 are in direct engagement, but the gears 18 and 19, on the contrary, are connected with one another by an intermediate wheel 20. The latter imparts the rotation of the toothed wheel 18 to the pinion 19, so that this rotates simultaneously with, but in a direction opposite to, the pinion 9. The latter is not firmly connected with the shaft 8 as in the known arrangement, but by a detachable clutch, as clearly shown in Fig. 6. The pinion 19 is connected in like manner by a clutch with the shaft 8. To this end, the two pinions 9 and 19 have incisions 23 and 24, respectively, in their hubs 21 and 22, respectively. Driving pins 25 and 26, secured in the rod 27, can be introduced into these incisions by means of a rod 27 movable longitudinally in the hollow shaft 8. The distance between the pins 25 and 26 is so much greater than the distance between the hubs 21 and 22 that the pins can only engage alternately in the hubs of the wheels. Behind the pin 26 is a ring 30 loose on the shaft 8 and a powerful spring 31 which acts on the pins 25 and 26 and the rod 27. The spring abuts against a ring 32 secured on the shaft 8 and tends to place the pin 26 into the slot 24 of the hub 22 and simultaneously to remove the pin 25 out of the slot 23 in the hub 21. The pinions 9 and 19 are prevented from moving longitudinally along the shaft 8. The rod 27 projects beyond the end of the shaft 8 and has here a spherical face 35 which lies in a spherical face 36 of a lever 37, as clearly shown in Fig. 5. This lever is rigidly connected with an axle 38 and thereby with the lever 39 secured on the same axle. The lever 39 has

a roller 40 at its top end and an extension 41. This abuts against the arm 43 (Figs. 3 and 5) of an angle lever which can rock around the pivot 44 and has an arm 45 extending vertically upward. A draw rod 46 is pivoted at 47 to the arm 45 and at 48 to a two-armed lever 49, 50. This lever is fulcrumed on the pivot 51 and can reciprocate with this pivot secured in a lever 52 which rotates with the shaft 53 and the arm 54. The bottom end of the lever 50 is located above the rear end of the shaft 56 carrying at its front end the lever 76 (Figs. 1 and 3) which serves for throwing into gear the casting apparatus and for controlling the line-transferring carriage 77, it being connected with the latter by a rod 76a. When the assembling elevator E of the machine rises the line-transferring carriage 77 is liberated in known manner from a catch 80 and then moves under the influence of a spring 78, which is attached to the lever arm 79 secured on the shaft 56, with the set line to the first elevator H (Fig. 1). The lever arm 57 carrying the roller 58 participates in the rotation of the shaft 56 which takes place. The roller finally arrives in its extreme position against a click, whereby the latter is released and causes the main clutch of the casting apparatus to be engaged. This and the other occurrences in the casting apparatus are not material for the mechanism which is to be described.

On the bushing 59, by means of which the lever 57 is secured on the shaft 56, is a projection or lug 60 which is located approximately vertically under the bottom end of the lever 50. The position of the lug is selected such that the line connecting its front face with the center of the shaft in the normal position forms approximately an angle of 45° with the vertical and that it approximately coincides with the vertical when the shaft 56 has rotated out of its normal position into its extreme position for actuating the driving clutch of the machine. It will be readily understood that the point of the lug moves, during this rotation, along an arc and that this movement can be resolved into a horizontal and a vertical component. The two components of the movement are utilized in various ways in the apparatus.

As long as no change of mold is to take place the bottom end of the lever 50 is at such an elevation that the lug 60 does not contact with the lever arm 50 during a rotation of the shaft 56. This elevation is maintained by a locking device which contacts with the lever arm 54, and the arm 52 and the lever 49, 50 are thereby prevented from descending. This locking device comprises a locking lever 62 fulcrumed on the axle 63 and pivotally connected to a rod 65. This connecting-rod 65 is connected by the

pin 66 with the end of the lever 67 fulcrumed on the shaft 68. The latter carries at the other end another lever arm 68^a having a roller 69. Above the latter is a segment 71 which is fulcrumed on the pivot 70 and has a projection 72 and a handle 73. If the handle be reciprocated, at each reciprocation the roller 69 is pressed downward by the projection 72 of the segment 71. Each reciprocation of the handle 73 causes a change of mold, the described apparatus working as follows: When the roller 69 is pressed downward the rod 65 and the locking lever 62 are lifted. The latter slides off the end of the arm 54 and releases the same. Owing to the weight of the lever 49, 50 the arm 52 carrying this lever rocks around the shaft 53 and drives the arm 54. When the roller 69 has passed the projection 72 on segment 71 it returns into its normal position, the locking lever 62 remaining on the broad end of the arm 54. The rod 65, being guided by the pivot 64 in an oval slot and thereby independently of the locking lever 62 falls immediately back into its bottom position and by its excess weight presses the roller 69 against the segment 71 thus preventing an accidental movement of the latter. When the arm 54 is released, the lever 49, 50 moves downwardly longitudinally and its bottom end arrives in front of the lug 60. During the subsequent movement of the line-transferring carriage, namely when a line is next conveyed from the setting to the casting position, the lug drives the bottom end of the lever 49, 50 and moves this laterally from left to right and, in addition, the entire lever 49, 50 upward. Owing to the latter movement, which is due to lug 60, the lever arms 52 and 54 are returned into their normal positions; the locking lever 62 again falls in front of the lever arm 54 and holds the same until it is released afresh, and the bottom end of the lever 49, 50 is out of reach of the lug 60 as soon as this has returned into its normal position. Simultaneously with the upward movement, however, a lateral movement of the lever arm 50 occurs, the same rocking around the pivot 51. This lateral movement is transmitted in the opposite direction by the arm 49 and the draw-rod 46 to the angle lever 43, 45 rocking around the pivot 44. In consequence of this movement the arm 43 releases the extension 41 of the lever arm 39, and the lever 37 connected with the latter now moves under the action of the rod 27 in the shaft 8 and the spring 31 influencing this rod in the longitudinal direction of the shaft 8. The pin 25 is removed from the slot 23 in the hub 21 and the pin 26 is simultaneously pushed into the slot 24 of the hub 22. Thus the driving gear of the shaft is reversed, so that when the main shaft is next thrown into gear the shaft 8 is driven by

means of the wheels 12, 18 and 19, 20 in the direction opposite to the normal. This opposite rotation is imparted to the mold-wheel, so that the mold 2 utilized immediately before does not arrive into the casting position, but the mold 3. After the completion of the first quarter-revolution of the mold-wheel the change gear of the wheel must be reversed again, in order that the mold brought into the casting position may arrive by means of a three-quarter revolution in the direction of the arrow 6 into the ejection position after the cast is finished. To this end, the rod 27 having the two driving pins 25 and 26 must be returned into its original position directly after the completion of the first quarter-revolution of the mold wheel. This is brought about by means of a cam 75 which is provided on the main shaft 16 and coacts with the roller 40 on the lever arm 39. While the mold-wheel itself is at rest on account of the casting, the main shaft 16 rotates and the cam 75 returns the roller 40, the levers 39 and 37 and the pins 25, 26 into their original, normal positions. The driving gear of the mold-wheel is thereby reversed afresh so that the wheel rotates again in the ordinary direction. At the beginning of the subsequent casting operation the mold 3 is in the ejection position and owing to the ordinary rotation of the wheel 1 arrives into the casting position 5. The mold 3 remains in use until the mold 2 arrives again into the casting position 5 owing to a new temporary reversal of the rotation of the mold-wheel.

It follows from the above that the change of mold takes place, if occasioned by means of the handle 73, when the line in question is conveyed from the setting to the casting position. If a line be situated between the setting and casting positions, in the so-called waiting position the shaft 56 and the lug 60 have turned so far that the bottom end of the lever 49, 50, when released in this moment does not fall in front of the lug 60 but onto the back thereof. Consequently, the end of the lever arm 50 is not driven when the transferring of said line is going on but remains in the disengaged position until the lug 60 returns into its normal position, which can only occur when the line-transferring carriage has delivered the line situated in the waiting position to the first or casting elevator.

The cam 75 is formed in such manner that it only admits of the reversal of the driving device when the casting apparatus is located in the ejection position or in the rest position. In each intermediate position the cam 75 coacts with the roller 40 and thereby prevents reversal until the casting operation is finished.

Mechanism for adjusting the line trimming blades has to be combined with the

- means for changing the mold. To this end, each of the molds 2 and 3 has at 96 (Fig. 7) an incision, behind which a hole 97 is provided in the body of the mold-wheel. At 5 the bottom of each incision is an abutment face 98 which determines the exact position of one of the two trimming blades or cutters and is of varying height according in each instance to the width of the mold.
- 10 In Figs. 9 and 10 the mold is illustrated in cross-section in two different positions opposite the blades. Of the two blades or cutters 100 and 101 the former is stationary whereas the latter is arranged to rock 15 around an axle 102. This axle is journaled in an adjustable holder 103 secured by means of screws 104 to the body 106. The latter is connected by means of screw-bolts 107 with the frame 108 of the matrix-clamp- 20 ing device commonly called the vise. The holder 103 can be so adjusted by means of an attachment screw 109 and two adjustment screws 110 (Figs. 8 and 9) that the edge 111 of the blade 101 is parallel with 25 the edge 112 of the blade 100. The blade 101 is not connected directly with the axle 102 but with a support or carrier 113 secured on the axle 102. On this support is an abutment or arm 114 which enters into 30 the incision 96 in the mold as soon as the mold is opposite the blades and is caused to approach the latter by the machine. Further, a body 115 having two arms 116 and 117 is journaled on the axle 102; these arms 35 enter into the movable abutments or pins 118 and 119, respectively, which move in guiding bushes 120 and 121, respectively. These guides or bushes 120 and 121 are slotted at 122 (Fig. 9). Likewise, the pins 118 and 40 119 have slots into which the lever arms 116 and 117 respectively enter. Further, there are connected with the body 115 which carries the lever arms 116 and 117 two additional lever arms 125 and 126, against which 45 the ends of a leaf spring 127 press and thereby tend to rotate the body 115 carrying said arms so that the pins 118 and 119 are shifted forward as far as possible. Two faces 131, one of which is provided on each 50 of the arms 116 and 117 (Fig. 9) now drive the body carrying the blade 101 by means of the faces 129 provided on this body opposite to the faces 131 (Figs. 8, 9 and 10) so far that the edge 111 of the blade 101 is 55 removed as far as possible from the edge 112 of the blade 100. The arm rigidly connected or integral with the body 113 also participates in this rotation. If the mold-wheel 1 carrying the mold 2 is now caused 60 to approach the blades, which is brought about automatically by the machine before the ejection of the line in well-known manner, two stops or abutments 133, which are integral or rigidly connected with the mold, 65 opposite to the pins 118 and 119, press on

these pins and thereby rock the levers 116, 117, 115 around the axle 102 against the action of the leaf spring 127. The spring 134 tends to impart the rotation of the body 115 to the body 113 and the blade 101, and the body 113 yields to this force until the lever 114 abuts against the face 98 of the mold 2. At this moment the correct distance between the edges 111 and 112 of the blades is obtained. The further rotation of the body 115 only compresses the spring 134 thereby securing the position of the blade 101. The ejector 135 now begins to push the cast line 136 out of the mold 2 and conveys it between the edges 111 and 112 into the galley 137 in front of the blades (Fig. 1). After the mold has receded the leaf spring 127 returns the body 115 having the arms 116 and 117 and the pins 118 and 119 into their normal positions. The abutment faces 131 on the lever arms 116, 117 drive the body 113 and the blade 101 on the same by means of the faces 129.

The thickness of the line to be trimmed is determined by the distance between the edges of the blades 101 and 100. This distance depends on the position of the face 98, because this limits the movement of the blade 101 by means of the lever arm 114. The face 98 is on the body forming the mold and can be so made on each individual mold that, when the mold in question approaches the blades, the blade is positioned corresponding to the width of the mold. The blades can be adjusted exactly, without departing from the scope of the invention, 90 solely by the stops or abutments 133 (Figs. 7, 9 and 10), in which event the stop 98 becomes superfluous. This is without significance for the essence of the invention. 95 Namely, according to the invention the blades 100 and 101 are adjusted for a definite line-body or width of mold by stops or abutments which are arranged on the mold itself and which cause the blades to be 100 adjusted whenever the mold is changed. The special advantage of the stops 133 is that the spring 134 does not require the extensibility requisite for the entire movement of the blade carrier 113 and therefore 105 can be selected very powerful in spite of the limited space, so that the movable blade 101 is held securely in its operative position. But it is necessary, however, that the stops or abutments 133 be approximately adapted 110 to the width of the molds and bring about a rough adjustment of the blade 101.

As follows from the above, the distance between the blades is adjusted each time, corresponding to the width of the mold used 115 and therefore changes automatically when a different mold is used. To change the mold and to make the requisite fresh adjustment of the blades requires only one single manipulation, namely a movement of the lever 120 125 130

73. The segment 71 on this lever, which operates the other members for adjusting the mold and blades, may be connected with an existing handle, *e. g.* one serving in machines having several magazines for changing the latter, so that when the magazine is changed a change of mold occurs automatically.

The above described illustrative embodiment of the invention can be modified in manifold ways. The mold-wheels, for example, may contain an optional number of like or different molds. Then when one of these molds arrives after use into the ejection position, every other mold in the wheel can be brought into the casting position by a partial rotation of corresponding amount and direction. These partial rotations can be brought about readily by means of reversible toothed wheel gearing of suitable ratio of transmission. The arrangement of a large number of reversible gears is well known generally in machine construction, *e. g.* in motor-cars. Also it is not necessary for the partial rotation serving for placing a mold into the casting position to take place at the beginning of the entire casting operation, but otherwise it must take place between the ejection of one line and the casting of the next.

What I claim as my invention, and desire to secure by Letters Patent is—

1. In a line-casting machine, the combination with a main shaft, of a mold-carrier carrying a plurality of molds, driving means driven by said shaft for driving said mold carrier and alternately bringing one of said molds into the casting and ejecting positions, additional driving means, driven by said shaft, adapted to drive said mold carrier and thereby automatically bring one of said molds from a non-ejecting position into the casting position, and controlling means for controlling the latter driving means.

45 2. In a line-casting machine, the combination, with a main shaft, a mold carrier carrying a plurality of molds, driving mechanism driven by said shaft for driving said mold carrier and alternately bringing one of said molds into the casting position and into the ejecting position, and line-transferring mechanism, of driving means driven by said shaft and adapted to drive said mold carrier and automatically bring one of said molds from a non-ejecting position into the casting position, controlling means for controlling the operation of said driving means, connecting means for connecting said controlling means with and disconnecting the same from said line-transferring mechanism, and means for operating said connecting means.

3. In a line-casting machine, the combination with a main shaft, and a wheel having toothed segments secured thereon, of a

mold carrier carrying a plurality of molds, a plurality of driving mechanisms driven intermittently by said wheel and adapted to drive said mold carrier in different directions, and manually controlled connecting means for operatively connecting said mold carrier with one of said driving mechanisms. 70

4. In a line-casting machine, the combination with a main shaft, and a wheel having toothed segments secured thereon, of a mold carrier carrying a plurality of molds, a plurality of driving mechanisms driven intermittently by said wheel and adapted to drive said mold carrier in different directions, connecting means normally connecting said mold carrier with one of said driving mechanisms, shifting means for shifting said connecting means for connecting another of said driving means to said mold carrier, manually controlled means for actuating said shifting means, and means for returning said shifting means to their normal position. 75 80 85

5. In a line-casting machine, the combination, with a main shaft, and a wheel having toothed segments secured thereon, of a mold carrier carrying a plurality of molds, driving mechanism, comprising automatic reversible gearing, driven intermittently by said wheel and driving said mold carrier, means normally holding said gearing non-reversed, manually operated levers for actuating said means and reversing said gearing, and a cam on said shaft for returning said means and said gearing into 90 95 100 their normal positions.

6. In a line-casting machine, the combination, with a main shaft, a wheel having toothed segments thereon, and a line transferring mechanism, of a mold carrier carrying a plurality of molds, driving mechanism adapted to drive said mold carrier to different extents and in different directions, controlling means controlling the actuation of said driving means, connecting means for connecting and disconnecting said controlling means to said line-transferring mechanism, and manually operated controlling means for controlling the connection between said former controlling means and 105 110 115 said line transferring mechanism.

7. In a line casting machine, the combination with a main shaft, a wheel having toothed segments secured thereon, and spring-operated line-transferring mechanism, of a mold carrier carrying a plurality of molds, driving mechanism comprising automatic reversible gearing, driven intermittently by said wheel and driving said mold carrier, levers adapted to reverse said gearing and normally holding said gearing non-reversed, locking means for locking said levers in their normal position and adapted to be released by said line-transferring mechanism, connecting means for operating 120 125 130

connecting said locking means with and disconnecting the same from said line-transferring mechanism, manually-operated controlling means for controlling said connecting means, and a cam on said main shaft for returning said gearing into its normal position after the same has been reversed.

8. In a line-casting machine, the combination, with a main driving wheel having toothed segments, of an axle carrying a bevel wheel adapted to mesh therewith, two spur wheels on said axle, a mold-wheel having a plurality of molds, a hollow, perforated shaft, a gear wheel on the latter meshing with the mold-wheel, two pinions each having a slotted hub loose on the shaft, one of said pinions meshing with one of said spur wheels, a gear meshing with the other pinion and the other spur wheel, a rod movable axially in said shaft, two pins secured in the rod, projecting out of the shaft and adapted to enter alternately into the slots in the hubs in said pinions, and a compressed spring on said shaft abutting against one of said pins and tending to force the same into the appertaining slot.

9. In a line-casting machine, the combination of a mold carrier having a plurality of molds, each mold having a plurality of sets of stops arranged corresponding to the width of the mold, and an adjustable line-trimming device, said line-trimming device comprising a movable blade having abutments adapted to coact with one set of said

stops, a spring-pressed intermediate member 35 adapted to coact elastically with said abutments and press the same against said set of stops on the mold, and movable abutments coacting with said intermediate member and adapted to coact with another set of stops on 40 the mold, for the purpose specified.

10. In a line-casting machine, the combination of a mold carrier having a plurality of molds, each mold having a plurality of sets of stops arranged corresponding to the 45 width of the mold, and an adjustable line-trimming device, said line-trimming device comprising a fixed blade, a holder mounted movably relatively to the fixed blade, a movable blade pivotally mounted in said 50 holder, said movable blade having abutments adapted to coact with one set of said stops, a spring-pressed intermediate member adapted to coact elastically with said abutments and press the same against said set 55 of stops on the mold, and movable abutments coacting with said intermediate member and adapted to coact with another set of stops on the mold, for the purpose specified.

60

In testimony whereof I have signed my name to this specification in the presence of two subscribing witnesses.

HEINRICH DREWELL.
